SKIRT HANGER

John V. Rowan, University City, Mo., assignor to
 Lee-Rowan Company, St. Louis, Mo., a corporation of Missouri

Application April 16, 1949, Serial No. 87,905

3 Claims. (Cl. 223—95)

1

This invention relates to skirt hangers, its principal object being to produce a hanger which may be laterally adjusted to fit the waistband of any skirt, effect gripping engagement therewith, and lock the hanger in this adjusted position, all in one operation. The greatest advantage of the invention is the saving of time and effort by making it possible to accomplish this simultaneously by merely exerting an upward pull on the hook by which the hanger is suspended when in use, another advantage being that the locking mechanism may be released, with consequent disengagement of the skirt from the hanger, by a light touch of the user's finger. Other features of the invention are its simplicity and therefore low cost of manufacture, and the fact that it will give long service with ordinary usage.

In the drawings:

Fig. 1 is a front or rear elevation of the skirt hanger showing it in retracted condition in full lines and in operative, extended position in dash lines.

Fig. 2 is a side elevation of the skirt hanger shown in Fig. 1.

Fig. 3 is an enlarged, cross sectional view taken on line 3—3, Fig. 2, showing particularly the locking mechanism of the skirt hanger.

Fig. 4 is an enlarged detail view of a portion of the mechanism for gripping the skirt band as shown in Fig. 1.

The invention comprises a horizontal tubular member 1 having oppositely disposed apertures 2 in its upper and lower walls, said apertures being equidistant from the ends of the tubular member 1. A vertical rod 3 is slidably positioned within the apertures 2 so that it extends above and below the tubular member 1, and at its upper end the rod 3 terminates in a hook 4 by which the hanger may be suspended from a support (not shown) when in use.

A hollow element 5 is rigidly secured at the central portion of the tubular member 1, the element 5 being substantially tubular but having a rounded upper end, which is apertured as at 6. The hollow element 5 is also apertured, as at 7, in both its side walls to permit passage through said element 5 of the tubular member 1. The apertures 2 of the tubular member 1 and the aperture 6 in the element 5 are in alignment with each other, so that the rod 3 passes through and extends upwardly beyond the element 5 and downwardly beyond said element, as shown clearly in Figs. 1 and 3.

A pair of horizontally extending rods 8, one on each side of the rod 3, are slidably positioned

within the tubular member 1. Each of the rods 8 is of such length as to extend from a point near the rod 3 outwardly a short distance beyond the tubular member 1, at which point said rod 8 is bent at a right angle, as shown at 9, to provide a downwardly depending vertical portion 10, each portion 10 being surrounded by a casing 11 of rubber or any similar material which offers a good gripping surface.

10 Interiorly of the tubular member 1 and surrounding the rods 8 I provide a coil spring 12 which extends in its retracted condition the full length of said tubular member and protrudes slightly therefrom at each end, and at the right angle bend 9 of each rod 8 I attach a retaining clip 13, the respective outer ends of the coil spring 12 being secured to said retaining clips to prevent displacement of said coil spring from the rods 8.

20 Within the upper portion of the hollow member 5 a coil spring 14 surrounds the vertical rod 3, the upper end of the coil spring contacting the inside of the upper rounded wall of the element 5 and the lower end of said coil spring resting upon a lever 15 inside said element 5. The lever 15 is provided with an aperture 16 which surrounds the rod 3 and is of slightly larger diameter than said rod, and said lever is of such length that one of its ends is positioned inside of the hollow member 5 and its opposite end 17 protrudes outwardly beyond the element 5 through an aperture 18 in the wall of said element 5, the aperture 18 being of slightly greater width than the thickness of the lever. The mechanism just described is most clearly illustrated in Fig. 3 and constitutes the locking mechanism of the device.

It will be observed from Fig. 1 that the vertical portions 10 have flattened sections 10' at their upper ends adjacent the rods 8, and a pair of bars 19 are pivoted, as at 20, one to each of the flattened sections 10 and extend downwardly in a diagonal direction when the device is in collapsed condition to the lowermost end of the rod 3, where they are pivoted to each other and also to the rod 3 by a pivot pin 21, said pivot pin also extending through the rod 3 and being rigidly secured thereto. Both the upper and lower ends of the bars 19 are flattened, as shown in Fig. 1, to facilitate pivoting thereof. The lower portion of the rod 3 is surrounded by a coil spring 22 which rests upon the pivotally connected lower ends of the bars 19.

In operation the procedure is as follows:

To secure a skirt to the hanger the ends of the

skirt's waistband must first be fastened together. The tubular member 1 is inserted horizontally into the skirt band and the hook 4 is then pulled in an upward direction, drawing up with it the ends of the bars 19 where they are pivoted at 21, and as these pivoted ends move up the upper ends of said bars 19, through their pivotal connection with the portions 10', exert an outward push on the outer ends of the rods 8. This operation is continued until the portions 10 are extended to such a distance that they come into tight contact with the waistband, where gripping engagement is effected between the waistband and the portions 10 by virtue of the casings 11 on said portions 10, at which time the device will have assumed the position shown in dash lines in Fig. 1. The coil spring 22 is now in contracted condition and in contact with the tubular member 1, and the coil spring 12 has been extended with the rods 8.

The skirt and hanger are retained in the position just described by the gripping engagement between the rod 3 and the diagonal walls of the aperture 16 shown in Fig. 3, whereby the rod 3 is securely held in the raised position to which it has been drawn by the upward pull on the hook 4 as previously described, and the coil spring 22 has been contracted by the upward pull on the hook 4. With the parts in the position just described, the skirt hanger is in operative condition.

To release the skirt from the hanger, the above operation is reversed; that is to say, the lever 15 is pushed down, bringing the walls of its aperture into vertical position; this releases the rod 3, whereupon expansion of the spring 22 pushes the lower, pivoted ends of the bars 19 down, and as they assume their initial position (shown in full lines in Fig. 1) the rods 8 are drawn back into the tubular member 1 where they are held by the retracted spring 12. It is clear that the just described operation withdraws the portions 10 from contact with the waistband, which is thus detached from the hanger. At this point downward pressure on the lever 15 is released, whereupon pressure of the coil spring 14 upon said lever restores it to the inclined, locked position shown in Fig. 3.

I claim:

1. A skirt hanger comprising a vertical, spring-controlled suspension member and a hollow horizontal member slidably engaged therewith,

spring-controlled extension arms within said horizontal member and provided with skirt-gripping elements, pivoted connecting means between said extension arms and said suspension member, and a spring-controlled lock including an operating lever engaged with said suspension member, all of said parts being simultaneously operable upon sliding movement of said suspension member.

2. A skirt hanger comprising a horizontal tubular member and spring-controlled extension arms therein, a spring-controlled suspension member passing through said horizontal tubular member, gripping elements at the outer ends of said extension arms, upwardly diverging means pivotally connecting said gripping elements and said suspension member, and a spring-controlled lock associated with said suspension member, said skirt hanger being adapted to simultaneously adjust said extension arms to the waistband of a skirt, grip said waistband, and lock said hanger in adjusted position in a single operation.

3. A skirt hanger comprising a horizontal tubular member and spring-controlled extension arms therein, a vertical, spring-controlled suspension member passing through said horizontal tubular member, the outer ends of said extension arms being bent to provide elements for gripping the waistband of a skirt, a pair of rods pivotally connected to the lower end of said suspension member and pivoted, respectively, to said gripping elements, and locking mechanism including an element surrounding said suspension member and secured to said horizontal tubular member, and a spring-controlled lever in gripping engagement with said suspension member, said skirt hanger being adapted to simultaneously adjust said extension arms to the waistband of a skirt, grip said waistband, and lock said hanger in adjusted position in a single operation.
